(57) **CLAIM**

The ornamental design for a magnifier camera, as shown and described.

DESCRIPTION

FIG. 1 is a front view of a magnifier camera, showing our new design, shown in the closed position.

FIG. 2 is a rear view of the magnifier camera in the closed position.

FIG. 3 is a top view of the magnifier camera in the closed position.

FIG. 4 is a bottom view of the magnifier camera in the closed position.

FIG. 5 is a right side elevational view of the magnifier camera in the closed position.

FIG. 6 is a left side elevational view of the magnifier camera in the closed position.

FIG. 7 is a rear view of the magnifier camera in the opened position.

FIG. 8 is a front view of the magnifier camera in the opened position.

FIG. 9 is a top view of the magnifier camera in the opened position.

FIG. 10 is a bottom view of the magnifier camera in the opened position.

FIG. 11 is a right side elevational view of the magnifier camera in the opened position; and,

FIG. 12 is a left side elevational view of the magnifier camera in the opened position.

The broken lines represent unclaimed portions of the magnifier camera.
